(57) **CLAIM**

The ornamental design for round tree pot, as shown and described.

DESCRIPTION

FIG. 1 is a top plan view of a round tree pot showing my new design;

FIG. 2 is a front elevational view thereof;

FIG. 3 is a bottom plan view thereof;

FIG. 4 is an exploded view thereof; and,

FIG. 5 is an isometric view thereof.

The broken line shown in FIGS. 4 and 5 is for illustrative purposes only and forms no part of the claimed design.
